UNITED STATES PATENT OFFICE

100,808

DESIGN FOR A TREE STAND OR SIMILAR ARTICLE

Abraham Wolf, New York, N. Y., assignor to
Noma Electric Corporation, New York, N. Y., a
corporation of New York

Application June 16, 1936, Serial No. 63,322

Term of patent 14 years

To all whom it may concern:

Be it known that Abraham Wolf, a citizen of the United States and resident of New York, in the county of New York and State of New York, has invented a new, original, and ornamental Design for a Tree Stand or Similar Article, of which the following is a specification, reference being had to the accompanying drawing, forming part thereof, in which,

Fig. 1 is a perspective view of a tree stand embodying my design; and

Fig. 2 is a bottom plan view thereof.

I claim:

The ornamental design for a tree stand or similar article substantially as shown.

Dated, New York city, N. Y., June 11, 1936.

ABRAHAM WOLF.
